UNITED STATES PATENT OFFICE.

G. RALSTON AYRES, OF PHILADELPHIA, PENNSYLVANIA.

DESIGN FOR A HORSE-BLANKET.

SPECIFICATION forming part of Design No. 17,144, dated March 1, 1887.

Application filed January 17, 1887. Serial No. 224,659. Term of patent 14 years.

To all whom it may concern:

Be it known that I, G. RALSTON AYRES, a citizen of the United States, residing in Philadelphia, Pennsylvania, have invented a new 5 and original Design for Horse - Blankets, of which the following is a specification.

My design for a horse-blanket is fully shown in the accompanying drawings, Figure 1 being a side view of the complete blanket, and Fig. 10 2 an enlarged view, showing more clearly the character of the stripes of which the pattern of the blanket is composed.

This pattern consists of the parallel stripes A and B, extending transversely across the 15 blanket, the stripe A being made up of stripes a b b and the stripe B of stripes d, e, and f. The stripe a is wide, and the stripes b b are narrow and serve as edgings for the stripe a, the stripes d, e, and f being of substantially uniform width, which is somewhat less than that 20 of the stripe a. More than three stripes may, if desired, be employed in the stripe B without departing from the design.

The blanket has the back bar, D, curved 25 neck border E, front border, F, horizontal bar G, extending back from the junction of neck and front border, and diagonal bar I, extending from the inner end of the bar G to the neck border; and the blanket is also provided with 30 border stripes along the bottom and rear edges.

I claim—

1. The design for a horse-blanket, said design consisting of the parallel stripes A and B, extending transversely across the blanket and arranged closely side by side, the stripe A comprising the wide central stripe, a, with its narrow edging stripes b b, and the stripe B comprising a series of stripes, d, e, and f, of medium width, all substantially as described and shown. 35

2. The design for a horse-blanket, said design consisting of the back bar, the curved neck border, front, bottom, and rear borders, and the parallel transverse composite stripes A and B, extending from the back bar and 40 neck border to the bottom border, all substantially as described and shown. 45

3. The design for a horse-blanket, said design consisting of the parallel transverse composite stripes A and B, the back bar, the curved neck border, the front, bottom, and rear borders, and the horizontal and diagonal bars G 50 and I, all substantially as described and shown.

In testimony whereof I have signed my name to this specification in the presence of two subscribers 55 witnesses.

G. RALSTON AYRES.
